(57) **CLAIM**

The ornamental design for a dispensing spout, as shown and described.

DESCRIPTION

FIG. 1 is a front view of the dispensing spout;

FIG. 2 is a rear view of the dispensing spout;

FIG. 3 is a right side view of the dispensing spout, the left side being a mirror image of the right side;

FIG. 4 is a top view of the dispensing spout;

FIG. 5 is a bottom view of the dispensing spout;

FIG. 6 is a front view of an alternative embodiment of the dispensing spout; and,

FIG. 7 is a side view of an alternative embodiment of the dispensing spout.

Those features shown on phantom do not form part of the claimed design.
